UNITED STATES PATENT OFFICE.

CHARLES T. WESTLAKE, OF ST. LOUIS, MISSOURI, ASSIGNOR TO CAST STEEL LOCOMOTIVE ASH PAN COMPANY, OF ST. LOUIS, MISSOURI, A CORPORATION OF DELAWARE.

LOCOMOTIVE ASH PAN.

1,410,978.

Specification of Letters Patent. Patented Mar. 28, 1922.

Application filed November 11, 1919. Serial No. 337,133.

To all whom it may concern:

Be it known that I, CHARLES T. WESTLAKE, a citizen of the United States, residing at St. Louis, Missouri, have invented a certain new and useful Improvement in Locomotive Ash Pans, of which the following is a full, clear, and exact description, such as will enable others skilled in the art to which it appertains to make and use the same, reference being had to the accompanying drawings, forming part of this specification.

My invention relates generally to the ash pans of locomotives, and more particularly to a gravity door that controls the outlet opening in the lower portion of the ash pan hopper.

One of the principal difficulties encountered in the operation and successful use of locomotive ash pans arises from the leakage of air through crevices in the joints between the ash pan door and the edges of the door opening in the hopper. Ashes and cinders dropping into the ash pan from the locomotive fire box contain considerable unburned fuel, some of which is under combustion, and when this burning fuel lodges in the lower portion of the ash pan or the hopper, it is acted upon by the currents of air which leak through the small openings at various points around the door, and as a result, rapid vigorous combustion is produced. As a result of this combustion and the heat produced thereby, the ash pan and hopper are very frequently damaged to a considerable extent due to burning, warping and distortion. Obviously it is highly desirable that the joints between the door and the ash pan hopper be formed and maintained as nearly air tight as possible and it is the principal object of my invention to provide a relatively simple construction whereby a gravity door is utilized for closing the outlet opening in the lower portion of the ash pan hopper and to form the edges of the hopper around the opening and the edges of the door so that they will cooperate in maintaining practically air tight joints while the door is closed, thereby reducing to a minimum, if not entirely eliminating, the inlet of air through the joints between said cooperating edges.

The cooperating parts or engaging surfaces of the hopper and door are subjected to more or less wear due to the opening and

closing of the door, and if one part wears more than the other, damage resulting from entering air jets will immediately be started, and it is one of the objects of my invention to provide a relatively simple construction that will automatically take up any wear that may occur between the parts and thus cause them to remain practically air tight.

With the foregoing and other objects in view, my invention consists in certain novel features of construction and arrangement of parts, hereinafter more fully described and claimed, and illustrated in the accompanying drawings, in which-

Figure 1 is an elevational view of an ash pan of my improved construction. 70

Figure 2 is an end elevational view of the ash pan.

Figure 3 is an enlarged detail section taken approximately on the line 3—3 of Figure 1. 75

Figure 4 is a plan view of the gravity door utilized in connection with my improved ash pan.

Referring by numerals to the accompanying drawings which illustrate a practical embodiment of my invention, 10 designates the main body portion of a locomotive ash pan which may be of standard construction and which is positioned in the usual manner beneath the locomotive fire box. Depending from the ash pan is a hopper 11, preferably of cast metal, and provided with a pair of inclined bottom plates or walls 12 and 13 and preferably with a horizontal bottom plate 14. The lower edge of the bottom plate 12 terminates a short distance from the end of plate 14, thereby forming an ash discharge opening and formed on the underside of the lower edge of the inclined plate 12 and extending from one side wall of the hopper to the other is a depending flange or lip 15. The end 16 of plate 14 is inclined and offset slightly with respect to the main body portion of said plate, thereby forming on the inner face of said plate 14 near its lower edge a shoulder 17.

The lower portions of the side walls 11 at the sides of the discharge opening and at the sides of the lower portion of inclined bottom plate 12 are extended outwardly and thence downwardly to provide flanges 18 which are offset with respect to the immediately adjacent portions of the side walls of

the hopper, and projecting inwardly from the lower edges of these offset portions are flanges 19, the inner faces of which terminate in the same vertical planes with the inner faces of the side walls of the hopper. Such construction provides grooves or channels 20 between the lips or flanges 19 and the lower edges of the main body portions of the side walls of the hopper which grooves or channels extend from points immediately beneath the shoulder 17 upwardly beneath the depending flange or lip 15 and upwardly to the upper ends of the flanges 18.

The gravity door which normally closes the discharge opening consists of a substantially rectangular plate 21, preferably of cast metal, its side edges being arranged for sliding movement in the grooves or channels 20, and formed integral with the upper edge of this plate is a transversely disposed upwardly projecting flange or lip 22 which, when the door is closed, bears directly against or occupies a position immediately adjacent to lip or flange 15 on the edge of bottom plate 12.

The lower corners of the door are cut away on angles as designated by 23 so as to clear any possible accumulation of cinders in the lower ends of the channels or guideways 20.

Formed integral with the upper portion of door 21 are depending ears 24 in which is loosely mounted a transversely disposed rod 25. Any suitable mechanism may be utilized for imparting opening movement to the door, but, as illustrated, I prefer to utilize a mechanism including a link 26 that is connected to one end of the rod 25 and connects said link to the lower end of a second link 27, the upper end of the latter being pivotally connected to a bracket 28 that projects from the side wall of hopper 11. Links 26 and 27 are preferably duplicated upon the opposite side of the pan although not illustrated in the drawings. Pivotally connected to the lower ends of links 26 and 27 is one end of a push rod 29, the opposite end being connected to a suitable operating lever 30.

Inasmuch as the door 21 is free to slide through the inclined grooves or channels 20, said door will by gravity tend to move into position to close the opening and likewise by gravity will tend to retain such position.

While in closed position the lower edge of the door fits snugly beneath the overhanging shoulder 17 and the upstanding flange 22 on the upper edge of the door lies immediately beneath the lower edge of the inclined bottom 12 and behind the lip or flange 15 thereupon. Such arrangement together with the side edges of the door fitting snugly within the grooves or channels 20 form practically air tight joints between all four edges of the door and the adjacent

portions of the hopper; consequently the ingress of air into the hopper around the door is effectually prevented.

By virtue of the fact that the grooves or channels 20 are inclined there will be no tendency of ashes or like material to lodge therein while the door is open but if relatively fine material should accumulate in said grooves, such material will be forced downwardly through and discharged from said grooves by the downward movement of the door or upon return to closed position. The cut-away corners 23 compensate for any slight accumulation of ashes or the like in the extreme lower ends of the grooves or channels 20.

To open the door or move the same upwardly so as to permit the discharge of ashes from the hopper, lever 30 is actuated to shift rod 29 and links 26 and 27 into the positions shown by dotted lines in Figure 1, which movement slides the door upwardly through the grooves or channels 20 and after the ashes have discharged through the opening, the opening mechanism is released and the door will move to full closed position, by gravity. In the event that there is any wear between the edges of the door and the adjacent portions of the hopper, said door will automatically adjust itself to the new conditions and thus practically air tight joints will be formed between the door and ash pan while the door is in closed position.

The hopper wall 12 at whose lower edge is formed the outlet opening for the ashes is arranged at an angle with the horizontal equal to or greater than the angle of repose of loose or powdered material, about forty degrees (40°); and consequently the door, which closes said opening, and which moves in a plane parallel to the plane of the wall 12, cannot carry ashes with it. On the contrary, even though said door be but partially open, the ashes, seeking their angle of repose, will pass through the opening, and leave the door and its guideways comparatively clean and clear of ashes. No power is required to close the door operating at this angle. It is gravitating and self-closing.

I have shown a hood or deflector 31, preferably of cast metal, which is integral with the hopper or is applied to the hopper around the opening in the lower end thereof and over the guideways for the door, which construction is especially advantageous where the hopper is provided with a flushing pipe as the hood positively deflects the contents of the hopper downward when flushed by steam, air or water discharged over the top surface of the flat bottom of the hopper.

A locomotive ash pan of my improved construction is comparatively simple, is provided with a door that moves into closed position and maintains such position by

gravity, and the life or period of service of the ash pan is materially increased due to the arrangements which entirely eliminate the leakage of air into the lower portion of 5 the hopper, and consequently eliminate the possibility of destructive fire and heat within said hopper.

It will be readily understood that minor changes in the size, form and construction 10 of the various parts of my improved locomotive ash pan can be made and substituted for those herein shown and described, without departing from the spirit of my invention, the scope of which is set forth in 15 the appended claims.

I claim:

1. A locomotive ash pan comprising an inclined hopper plate having a discharge opening formed therein, a hood surrounding 20 said opening for directing material discharged therefrom, and a door slidably arranged for operation between said hood and said hopper plate.
2. A locomotive ash pan having an inclined hopper plate provided with a discharge opening, a guideway on each side of said discharge opening, a hood arranged outside of said guideways to direct material discharged through said opening, and a 25 door slidably mounted in the guideways between the hood and the hopper plate.
3. A locomotive ash pan having a wall member, a hopper bottom plate terminating

short of said member to provide a downwardly opening outlet, a gravity door slidably mounted on said plate arranged at an angle approximately the angle of repose of the ashes in the pan and cooperating with an edge of another wall of said pan for closing the opening in the hopper plate, 40 and a hood outside said door adapted to direct the flow of material discharged through said outlet.

4. In an ash pan, having an inclined hopper bottom plate, and a discharge opening 45 at the lower end of the plate, laterally extending recesses in said hopper plate adjacent to said opening, a transverse hopper plate at the ends of said opening and recesses, and a door for said opening received 50 and slidably supported in said recesses and having those corners beveled which, when the door is closed, are located at the intersection of said recesses with said transverse plate.

5. In a locomotive ash pan, an inclined hopper bottom plate, a downwardly opening outlet at the lower end of said plate, a door slidably mounted on said plate and adapted to close said outlet, and a hood outside of 60 said door surrounding said outlet and adapted to direct the flow of material discharged through said outlet.

In testimony whereof I hereunto affix my signature this 7th day of November, 1919.

CHARLES T. WESTLAKE.
